UNITED STATES PATENT OFFICE.

VALENTIN RETTERATH, OF INGOLSTADT, GERMANY.

DEVICE FOR MAKING CORRUGATED CYLINDERS.

Application filed January 3, 1924. Serial No. 684,176.

To all whom it may concern:

Be it known that I, VALENTIN RETTERATH, a citizen of the German Republic, residing at Ingolstadt, Bavaria, Germany, have invented certain new and useful Improvements in Devices for Making Corrugated Cylinders, of which the following is a specification.

The invention relates to a device for producing corrugations on cylinders such as are used in textile machines by means of rollers which are rolled in the direction of the longitudinal axis of the cylinder and thereby press grooves therein, the cylinder being rotated one corrugation space after each operation of the rollers. For this purpose rollers having a single circumferential rib have been used, but this has the disadvantage that edges are raised on both sides which must either be removed, or together with the edge of the adjacent groove may form an elevation or crest of a corrugation upon the formation of said adjacent groove. Apart from the fact that both possibilities require further expenditure of work, in the former case there is waste of material, whilst in the latter case a corrugation is produced, the crest of which has not the compact structure necessary for the proper and efficient operation of these rollers in continual use.

According to the present invention however the corrugations are produced by means of rollers having a plurality of circumferential ribs, the cylinder to be corrugated being rotated one corrugation space after each operation of the rollers. The advantage is thereby obtained that not only is the formation of an edge avoided, but the material pressed up out of the grooves formed in the cylinder is pressed into the elevated parts or crests of the corrugations so that a compact structure of the material is maintained.

In the accompanying drawing I have shown an example of an apparatus for carrying my invention into effect. Fig. 1 is a diagrammatic view, partly in section, of the roller and the cylinder to be corrugated thereby, Fig. 2 is a front view and Fig. 3 a side view, partly in section, of an assembled device for carrying out my invention.

The rollers *a* are provided with a plurality of ribs which may be of annular or spiral form, four such annular ribs, *b*₁, *b*₂, *b*₃, and *b*₄ being shown in the drawing. The rollers *a* are further mounted in such a manner that they will rotate upon the cylinder

c and impress the corrugations thereon when said rollers are moved longitudinally of the cylinder. In the apparatus shown in Figs. 2 and 3 of the drawing the cylinder *c* is shown as being fixed in space, while the rollers together with their carrier *d* are movably mounted.

The process of rolling the corrugations of the cylinder is performed in such a manner that the ribs of the rollers *a* will be impressed during the first operation of the rolling process according to my invention, as much as possible, their entire depth into the cylinder *c*. Between the outer ribs, *b*₁, and *b*₂, as well as between the ribs *b*₃ and *b*₄ there will result a pronounced elevated part while the inner ribs *b*₂ and *b*₃ will form a nearly finished elevation. For the rolling process according to my invention it will be sufficient to employ only one pair of ribs on the roller. It is, however, of advantage to employ a plurality of ribs as shown in Fig. 1 for the purpose of carrying out the process of rolling in subsequent steps of which the preceding is preparatory to the subsequent step.

For accelerating the process of rolling according to my invention it will furthermore be of advantage to employ a plurality of rollers and evenly distribute said rollers around the cylinder in a plane perpendicular to its axis, as shown in Figs. 3 and 4. In the arrangement according to Figs. 3 and 4, the roller carrier *d* is provided with four rollers which are spaced from each other by an angle of 90 degrees thus holding the cylinder between themselves and forming a guide for the latter.

The rollers *a* are mounted upon the roller carrier *d* by means of swinging arms *e* pivoted to guiding members *g*, which latter are mounted within the hollow arms of the roller carrier *d*, to permit a radial adjustment of the guiding members and the rollers. Springs *f* serve to press said guiding members *g* in outward direction with their oblique rear parts against the inner oblique surface of the rim or handwheel *h*, which is screwed upon the roller carrier *d*. Thus, by rotating said rim in one or the other direction, the rollers will be radially adjusted and enter more or less into the surface of the cylinder *c*.

The process of rolling the corrugations according to my invention will be as follows: The cylinder with its diameter exact-

ly turned off is mounted within a feed mechanism, whereupon the roller carrier is moved in the direction of the arrow shown in Fig 3 by means of machine power. During rear-
ward motion of the roller carrier the rollers will swing out toward the left, so that they will not be able to perform the rolling process. Before the next step of the rolling operation, the cylinder will be fed forward 10 according to the pitch of the corrugation as indicated by the arrow shown in Fig. 1, and thereupon the rolling is continued. If a cylinder has thus been fed forward by an angle of 90 degrees, the second step of the process of rolling may be performed by rotating the rim h by hand and adjusting the rollers to a greater depth of rolling, whereupon the aforementioned steps of rolling may be repeated. The chamber i in the roller-carrier d is kept filled with grease, in order to secure proper lubrication. In order to corrugate the cylinder so as to obtain corrugations of uneven width, it is advisable to make the circular ribs on the rollers 25 of uneven depth.

It is to be understood that the invention is not limited to the precise construction set forth but that it includes within its purview whatever changes fairly come within 30 either the terms or the spirit of the appended claims.

I claim:

1. A device of the character described for forming longitudinal ribs and grooves in cylindrical bodies, comprising a carrier, movable longitudinally of the cylindrical body, a plurality of roller carrying elements mounted in said carrier for radial movement

with respect to the cylindrical body, and a roller supported from each of said elements, 40 each roller having a plurality of circumferential ribs formed thereon.

2. A device of the character described for forming longitudinal ribs and grooves in cylinders, comprising a carrier movable 45 longitudinally of the cylinder, a plurality of elements mounted in said carrier for radial movement with respect to the cylinder, arms pivotally connected to said elements and rollers carried by said arms each 50 of said rollers having a plurality of circumferential ribs formed thereon.

3. A structure as recited in claim 2, in combination with a member adapted to act upon all of said elements simultaneously, to 55 move said elements and the rollers forcibly toward the cylinder.

4. A structure as recited in claim 2, in combination with an annular member movable axially upon the carrier and having a 60 cam action upon the outer ends of said first named elements, to move said elements and the rollers forcibly toward the cylinder.

5. A structure as recited in claim 2, in combination with spring means tending to 65 move said elements radially outward, and an annular member threaded upon the carrier and having a cam action upon the outer end of said elements to force all of said elements simultaneously and forcibly inward to bring the rollers into forcible engagement with the cylinder.

In testimony whereof I have hereunto affixed my signature.

VALENTIN RETTERATH.
